UNITED STATES PATENT OFFICE.

WILLIAM J. DEMMING, OF LAKWOOD, OHIO, ASSIGNOR TO THE AMERICAN MULTIGRAPH COMPANY, OF CLEVELAND, OHIO, A CORPORATION OF OHIO.

APPARATUS FOR REMOVING PRINTING STRIPS FROM HOLDERS.

Application filed November 10, 1926. Serial No. 147,469.

Patent No. 1,438,580, granted December 12, 1922, to my assignee, The American Multigraph Company shows and claims an assembled printing form comprising a holder having raised overhanging projections and embossed printing strips mounted on such projections and held in place by inwardly projecting edge flanges extending beneath the projections.

10 The object of the present invention is to provide a simple machine for readily removing such embossed strips from such holder, whereby whenever the form on the holder becomes obsolete, the holder may be readily 15 rendered available for a new form.

My invention is well adapted for cooperation with a holder carrying a few strips and utilizable as an address plate. The embodiment of the invention shown in the 20 drawings is designed especially for use with such composite address plate of the particular form illustrated and claimed in applications Nos. 106,792 and 128,760 filed May 5th, 1926, and August 12th, 1926, respectively, by Henry C. Osborn and assigned to 25 my assignee. Certain features of such plate are also covered in Patent No. 1,438,582 of B. J. Craig and application No. 76,298 filed December 18, 1925, by J. W. Macklin and 30 assigned to my assignee.

My invention is hereinafter more fully explained in connection with the drawings and the essential novel features are summarized in the claims.

35 Fig. 1 is a side elevation of my machine; Fig. 2 is a plan thereof; Fig. 3 is a vertical longitudinal section of the machine substantially as indicated by the line 3—3 on Fig. 2; Figs. 4 and 5 are cross-sections on planes indicated by the lines 4—4 and 5—5 on Fig. 3; Fig. 6 is a detail illustrating the plate retaining pawl, being an enlarged horizontal section indicated by the line 6—6 on Fig. 3; Fig. 7 is an enlarged vertical section illustrating the block carrying the stripping plungers; Fig. 8 is a perspective of one of such stripping plungers; Fig. 9 is a diagram in elevation illustrating the action of the stripping plungers, this view being in 40 the nature of a vertical cross-section on the line 9—9 on Fig. 2 with the cover plate for the plungers removed; Fig. 10 is a perspec-

tive of an address plate which may be readily stripped by the specific machine shown.

55 As shown in the drawings, the frame of the machine comprises a horizontal bed 10 having an edge skirt 11 which may terminate in outwardly extending feet 12. In the upper face of the bed is a longitudinal channel 12. The upper portion of this channel is comparatively wide, then it is narrower for a certain depth, and below this still narrower. In the widest or upper portion of the channel lies a sliding block 20 60 embraced by two longitudinal bars 21 connected to the block by pins 22. These bars extend a considerable distance beyond the end of the bed and are there pinned to an intermediate block 24. The bars 21 lie beneath a pair of gibbs 27 fastened by screws to the bed plate 10. There is thus provided a frame slidably mounted in ways sunk within the face of the bed plate.

70 Secured to the underside of the block 24 is a horizontal rack 30 which extends inwardly and occupies the narrowest portion of the channel 12 in the bed and is slidably retained therein by a plate 32 secured to the bed by screws on opposite sides of the rack. 75 Directly beneath the rack is a spur gear 40 80 projecting upwardly through an opening in the bed and meshing with the rack. This gear is rigidly mounted on a shaft 36 on the outer end of which is a hand lever 37 85 or other means for oscillating the shaft.

90 The gearing described is preferably so proportioned that when the handle extends outwardly as shown in Fig. 1, the rack and frame are in the outermost position, whereas when the handle extends in about the opposite direction, the rack and frame are in their innermost position. The bed plate beyond that portion which occupies the rack is either open as at 15 or cored out as at 16 95 to allow the passage of the rack.

95 The reciprocating frame above described furnishes means for moving an address plate beneath certain stripping plungers to be hereinafter described. The holder portion 100 of such plates may well be of the form shown in Fig. 10 comprising a sheet metal holder A having downwardly turned edges a with outward flanges a' and having on

its intermediate face upwardly extending corrugations a^2 from which extend lateral lips a^3 . Embossed printing strips indicated at B and having inwardly flanged edges b may be slid into place on the face of the corrugations with their flanges extending beneath the lips. Such strips are usually frictionally bound in place by slight indentations of their edges as shown and 10 claimed in application No. 50,155 filed August 14, 1925, by Clifton Chisholm and assigned to my assignee.

The present machine engages the plate A and shoves it along while the plungers to 15 be described engage such strips B as it is desired to remove, so that the plate is shoved out from under them.

The plates to be stripped are stacked in a vertical magazine comprising a pair of up- 20 right plates 40 which have base flanges 41 by which they are secured to the bed and have inwardly turned vertical edge flanges 42 which overhang the ends of the edge beads a^1 of the address plates. The plates 25 normally stand in this magazine on top of each other with the edge beads of each plate resting on the edge beads of the plate next below, except the bottom plate, the edge beads of which rest on the bars 21. 30 The forward portion of the bars 21 are recessed, as shown at 28 in Fig. 5 for a length as great as the length of the plate and to a depth corresponding to the thickness of the beads a^1 .

35 It results from the construction just described that when the reciprocating frame is moved to its extreme outward position by the handle 37, the stack of plates drops so that the beads of the bottom plate come into 40 the recesses 28 while the intermediate portion of such bottom plate rests on the block 20; then if the reciprocating frame is moved inwardly, the bottommost plate is carried along with it, while the remainder of the 45 stack is supported by the unrecessed face of the bars 21.

At the right of the magazine as shown in Figs. 1 and 2 is a transverse block 50 secured to the bed by screws passing through 50 base flanges 51. On its under side, this block is recessed at 52 to allow the passage of the reciprocating frame and plate. Mounted in a recess in the left hand vertical face of the block are a set of plungers 60 (as many as the total number of lines which may be carried to the plate) which are shown as rubbing against each other and held in place by a front plate 55 secured to the block and having an overhanging top 55 flange 56. Any of these plungers may be held in place to engage the corresponding strip and prevent its advancement while the plate is advanced beneath the block.

60 Mounted in kerfs in the upper face of the block 50 are series of levers 65 pivoted by

means of a transverse pin 66. There is one lever for each plunger 60, such lever engaging a notch 61 in the upper portion of the plunger. Mounted in horizontal cavities 57 in the block 50 are short latch rods 58, one 70 for each plunger 60, and pressed toward them by springs 59. The plungers 60 are provided with suitable V-shaped recesses 62 in which the noses of the respective latch rods are engaged. 75

When any plunger 60 is intended to be active, it is substantially in the position shown in Fig. 3, the latch 58 engaging its notch 62 and holding it in place. When, however, it is desired to move any plunger 80 to idle position, this is readily effected by depressing the outer end of the corresponding lever 65 which moves the plunger upwardly until it abuts the flange 56 of the front plate. The spring latch engaging the 85 face of the plunger will hold it in this elevated idle position until the plunger is depressed by its lever.

Assuming that the plungers are depressed to engage the strips to be removed, then as the reciprocating frame carries a plate toward the right out of the magazine, the plungers will engage the strips without engaging the plate and thus prevent advancement of the strips, so that the plate is shoved out beneath the strips. The plate is thus advanced beyond the plungers and is thereby cleared of such strips as it is desired to remove. Such removed strips drop through the opening 15 in the bed plate into a pile 100 as indicated at B¹ in Fig. 3.

As the plate, with some or all of the strips removed, comes to the right hand end of the stroke of the reciprocating frame, it engages and passes beyond a retaining pawl 70 (Fig. 105 6) which is pressed inwardly into its path by a spring 71. This pawl springs behind one bead of the plate; then as the reciprocating frame is returned toward the left, this plate cannot travel with it, and thus drops down idly onto the bed, as shown by the plate A¹ in Fig. 3. On the next stroke of the frame this plate A¹ is engaged by the end of the frame and is shoved to the extreme right over the receptacle which is 115 adapted to receive the cleared plates.

Fig. 9 is a diagram illustrating an action of the plungers 60 on the strips B. The lower faces of these plungers are inclined or curved, so that the bottom boundary of the set substantially corresponds to the curvature of the top of the plate A. The plungers in their lowered, or active position clear the projections of the plate, as indicated by the plunger 60^a which is directly 120 over the unoccupied lips a^3 . Such a lowered plunger however, would engage a strip mounted on these projections, as illustrated by the plunger 60^b which is abutted by the strip B. If, however, the plunger be lifted 130

by its lever 65 as illustrated by the plunger 60°, it is high enough to clear the corresponding strip B.

It will be seen that by a simple adjustment up or down of the plungers all of the strips may be removed as desired. For instance, it may be desired to clear the plate entirely, in which case all of the plungers are down; or it may be desired to leave on the plate only the salutation, in which case its plunger would be up and the remainder down, or in some instances, it may be desired to remove only the name and street address leaving on the plate the city and state address.

My machine is simple in construction and readily operable to effect a rapid clearing of the plates without injury to either plates or the strips.

20 I claim:

1. A machine for removing a printing strip from a holder comprising an abutment adapted to engage the strip and mechanism for progressing the plate across such abutment, whereby the strip is stopped while the plate continues to move.

2. A machine for removing strips from holders comprising a set of abutments adapted to engage the respective strips and mechanism for progressing the plate across such abutments, whereby the strips are stopped while the plate continues to move.

3. In a machine for removing printing strips from a holder, the combination of means for engaging the different strips, means to hold the holder and means for moving one of said means relative to the other to cause the simultaneous removal of several strips from the plate.

40 4. In a machine of the character described, the combination of means to hold a plate having surmounting printing strips, means to abut the ends of said strips individually, and mechanism for moving one of said means relative to the other.

5. The combination, with means for holding an assembled printing form comprising a plate with upstanding projections and surmounting embossed sheet metal printing strips, of a series of abutments, one for each strip, depending from above the path of the plate into position to be engaged by the strips while clearing the plate, and means for moving the plate across the abutments, whereby the strips are stopped and the plate shoved out from under them.

60 6. A machine for removing printing strips from a holder, comprising individual abutments for engaging the different strips, means to hold the holder, means for moving one of said means relative to the other to cause removal of the strips from the plate, and means for adjusting the individual abutments into and out of active position.

65 7. The combination, with means for hold-

ing an assembled printing form comprising a plate with surmounting printing strips, of a series of abutments, one for each strip, means for moving the plate across the abutments, and means for adjusting the individual abutments into and out of active position.

8. In a machine of the character described, the combination of a bed, a reciprocating frame thereon adapted to engage a form holder, and means for abutting the form members on the holder whereby the frame may shove the holder out from under the form members.

9. In a machine of the character described, the combination of a magazine adapted to hold a stack of address plates, a reciprocating frame movable beneath the magazine and adapted to shove the bottommost plate therefrom, and a stripper mechanism adapted to engage strips of such shoved plate and prevent their advancement while the plate is advanced.

10. In a machine of the character described, the combination of a magazine adapted to hold a stack of address plates, a means adapted to shove a plate therefrom, and a stripper mechanism is adapted to engage strips of such shoved plate and prevent their advancement while the plate is advanced, such stripper mechanism comprising individual members for the different lines settable into active or inactive position as desired.

11. The combination of a magazine adapted to hold a stack of address plates, a reciprocating frame adapted to engage the bottommost plate and shove it out of the magazine, means adapted to engage strips on the advancing plate and prevent their advancement, and means for preventing the return of the cleared plate.

12. The combination of a magazine adapted to carry address plates consisting of holders with surmounting printing strips, a receptacle adapted to receive cleared plates, mechanism for transferring plates from the bottom of the magazine to the top of the receptacle, and mechanism for clearing such plates of strips during such transfer.

13. The combination, with mechanism for clearing a plate of strips, of a frame for shoving the plate across the clearing mechanism, said frame having an opening through which the discharged strips may pass.

14. The combination of a magazine adapted to hold address plates having removable printing strips, a reciprocating frame movable beneath the magazine and having an intermediate opening through it, and a stripping device beyond the magazine adapted to prevent the advancement of strips, whereby the plate may be cleared of stopped strips and the strips dropped through the opening in the frame.

15. The combination of a magazine for address plates having removable strips, a receptacle for cleared plates, a reciprocating frame movable beneath the magazine and adapted to shove the bottommost plate toward the receptacle, a series of plungers located between the magazine and receptacle and adapted to stop the advancement of desired strips, and means for 10 adjusting such plungers to and from the path of travel of the reciprocating frame.

16. The combination of a magazine for address plates, stripping mechanism adjacent such magazine, a reciprocating frame 15 adapted to engage the endmost plate in the magazine and move it across the stripping mechanism, a rack carried by said frame, and an oscillating gear meshing with said rack.

20 17. In a machine of the character described, the combination of a bed having a channel in its upper face, a block and a pair of slide bars mounted in said channel and constituting a reciprocating frame, a rack 25 secured to said frame, an oscillating gear meshing with said rack, means for operating the gear, and a stripping device carried by the frame and having a set of plungers adapted to be individually positioned to 30 engage corresponding strips on the address plate.

18. The combination of means for advancing an address plate, a series of plungers mounted side by side and adapted in one 35 extreme position to engage the strips and in another extreme position to clear the strips,

and in each position to clear the plate, and a corresponding series of levers for operating the different plungers.

19. In a machine of the character de- 40 scribed, the combination of a bed, a reciprocating frame mounted thereon, a magazine for address plates carried by the bed, means for reciprocating the frame beneath the magazine, a block mounted adjacent the mag- 45 azine, a series of plungers slidably mounted in the block, a series of levers for operating the respective plungers whereby said plungers may be positioned to interrupt the movement of desired strips, there being pro- 50 vision for the discharge of the removed strips and cleared plate, and means for preventing the cleared plate returning on the back stroke of the frame.

20. In a machine of the character de- 55 scribed, the combination of a reciprocating frame, a magazine for address plates, means for reciprocating the frame beneath the magazine, a series of plungers slidably mounted, a series of levers for operating the 60 respective plungers, whereby said plungers may be positioned to interrupt the movement of desired strips, means for preventing the cleared plate returning on the back stroke of the frame, downwardly facing rack 65 carried by said reciprocating frame, a gear meshing with the rack, and a hand lever operating the gear.

In testimony whereof, I hereunto affix my signature.

WILLIAM J. DEMMING.
